US00D513072S

(12) **United States Design Patent** (10) Patent No.: **US D513,072 S**
(45) Date of Patent: **** Dec. 20, 2005**

(54) **PART IN A VENTILATION SYSTEM**

(75) Inventor: **Ola Berg**, Förslöv (SE)

(73) Assignee: **Lindab AB**, Bastad (SE)

(**) Term: **14 Years**

(21) Appl. No.: **29/187,104**

(22) Filed: **Jul. 28, 2003**

(30) **Foreign Application Priority Data**

Jan. 29, 2003 (SE) 03-0113

(51) LOC (6) Cl. **23-04**

(57) **CLAIM**

The ornamental design for part in a ventilation system, as shown and described.

DESCRIPTION

FIG. 1 is a perspective view of a part in a ventilation system showing my new design;

FIG. 2 is a perspective view thereof; and,

FIG. 3 is a right side elevational view thereof.

The component shown with broken lines is not considered to be a part of the claimed design.
